BY *Henry F. Parker* ATTY.

UNITED STATES PATENT OFFICE.

THOMAS F. GAYNOR, OF BROOKLYN, NEW YORK.

DESIGN FOR A COIN OR MEDAL HOLDER.

SPECIFICATION forming part of Design No. 22,816, dated October 3, 1893.

Application filed March 24, 1893. Serial No. 467,517. Term of patent 14 years.

To all whom it may concern:

Be it known that I, THOMAS F. GAYNOR, of Brooklyn, county of Kings, and State of New York, have invented and produced a new and 5 original Design for Coin or Medal Holders, of which the following is a specification.

The drawing is a perspective view of a coin or medal holder embodying my design.

A leading feature of my design consists in 10 a coin or medal holder having a reeded periphery simulating the reeding of a coin.

Another feature of my design consists in inwardly turned portions in connection with the feature before mentioned.

15 2 designates the holder consisting of a band

having its outer surface transversely reeded as at 4, and having inwardly turned portions 10.

It is to be understood that I do not confine my design to a reeding extending at right angles to the diameter of the holder, as a reeding extending at an oblique angle is within the terms of my design.

What I claim is—

The design for a coin or medal holder substantially as herein shown and described.

THOMAS F. GAYNOR.
